Atty.

UNITED STATES PATENT OFFICE.

JOHN J. ROSE, OF ELMWOOD, ILLINOIS.

WHIP-HOLDER.

SPECIFICATION forming part of Letters Patent No. 289,810, dated November 27, 1882.

Application filed November 13, 1882. (No model.)

To all whom it may concern:

Be it known that I, JOHN J. ROSE, a resident of Elmwood, in the county of Peoria and State of Illinois, have invented certain new and useful Improvements in Locks for Whips; and I do hereby declare that the following is a full, clear, and exact description thereof, reference being had to the accompanying drawings, and to the letters of reference marked thereon, making a part of this specification.

My invention relates to whip-holders; and it consists in the improved construction hereinafter fully described, whereby a whip-holder is produced that has many advantages over holders heretofore constructed.

In the accompanying drawings, forming a part of this specification, Figure 1 is a side elevation, showing my improved whip-holder applied to the section of a dash-rail. Fig. 2 represents a side view of the improved locking device used in connection with the whip-holder, the side casing of the said lock being removed. Fig. 3 is a section on the line *y y* of Fig. 1.

S S' represent the two sections forming the whip-socket proper, pivoted together at their center, as shown in Fig. 1. The section S, nearest the dash-rail, is provided with perforated ears *a a*, through which pass the threaded ends of screws N N, which, in connection with the clamp-plates G G', secure the pivoted sections S S' to the side rail, R, of the dash. A ring section, A, has an extension provided with perforations in its end face, to receive the threaded ends of screws N of the upper clamp-plate, G'. Two cam-sections, C C', are arranged inside the ring-section A, as seen in Fig. 3, the ends *b b'* of said cam-sections resting in bearings therefor formed in the upper side of the ring-section A. The ends *b b'* project through the side of the ring-section A, and carry rigidly on their extremities disks E E', which are toothed for a portion of their peripheries, as seen in Fig. 2, the said teeth meshing with each other. The end *b* of the cam-section C projects through the other side of the casing, and is formed square at its extremity to receive a key-lever, F. An upper ring-section, A', rests upon the ring-section A, and maintains the cam-sections C C' in proper position in their bearings in the upper face of the section A. The side of the ring-

section A on which the disks E E' are located is extended, as shown in Fig. 3, to permit the application of a cap, B', having secured to its inner side a pawl, I, pivoted upon a stud, J', and engaging the teeth of the disk E', as shown in Fig. 2. A leaf-spring, H, secured on a stud, J, attached to the cap B', has one end extending around and bearing upon the upper face of the pawl I, to maintain said pawl in engagement with the disk E'. A perforation, M, formed in the cap below the pawl, permits the insertion of a key or other device, to effect the raising of the pawl out of engagement with the teeth.

The operation of the device is as follows: The whip being inserted between the cam-sections C C', down into the socket formed by the pivoted sections S S', the lever F is moved so as to cause the cam-section C to revolve in its bearings, and resulting in the cam portion thereof moving toward and in contact with the whip-handle, the said rotation of the cam-section C causing the section C' geared thereto, to also move up and in contact with the other side of the whip-handle. The teeth on the disks E E' are so arranged with respect to the pawl that the previous movements of the cam-sections will not be interfered with by the pawl I; but any reverse movement, however, of said cam-sections is rigidly prevented by said pawl, and can only be effected by inserting a key or pin through the opening M and raising the pawl, as hereinbefore described.

From the foregoing it will be apparent that a whip-holding device constructed in accordance with my invention is easily secured in position, of simple construction, and effective in operation.

I am aware that whip-holding devices have been constructed with cam-sections geared together, and adapted to operate to rotate and clamp the whip-handle within the socket; hence I make no broad claim thereto; but I claim—

1. The combination, in a whip-holding device, of a ring-section, A, adapted to be adjustably clamped to the side of the dash-rail, two cam-sections having bearings in said ring-section, geared together as described, and a lever for effecting the approach or recession of said cam-sections, substantially as set forth.
2. The combination, in a whip-holding de-

vice, of a ring-section, A, a clamp for adjustably securing the same to the side of the dash-rail, two cam-sections having bearings in said ring-section, and disks E E', rigidly mounted on the ends of the said cam-sections outside of said ring-section, and geared together as described, a cap engaging the end of the ring-section covering the disks, and provided with

a spring-pawl engaging one of the disks, and a perforation, substantially as set forth.

In testimony that I claim the foregoing I have hereunto set my hand this 10th day of November, 1882.

Witnesses: JOHN J. ROSE.
A. L. TRACY,
A. M. SHAPLEY.
